[57] **CLAIM**

The ornamental design for a wall-mounted container for the protection and storage of safety glasses and goggles, as shown and described.

DESCRIPTION

FIG. 1 is a front elevational view of the wall-mounted container for the protection and storage of safety glasses or goggles showing my new design;

FIG. 2 is a rear elevational view thereof;

FIG. 3 is a right view thereof;

FIG. 4 is a left view thereof with the spring-loaded front lid in the open orientation;

FIG. 5 is a top plan view thereof; and,

FIG. 6 is a bottom plan view thereof.

It is understood that the interior walls of the container are flat and unornamented.
